ARTHUR P. BARRINGER, OF PITTSBURGH, PENNSYLVANIA, AND MASON A. JACKSON,
OF NEW YORK, N. Y.

TOOTHBRUSH CASE

Application filed February 6, 1929. Serial No. 337,977.

This invention relates to containers, and has particular reference to a toothbrush case.

At the present time, it is the general practice to hang toothbrushes openly on racks in 5 bathrooms or to place the same in the medicine cabinet. Obviously, this practice is unsanitary and subjects the bristles to dust, dirt, germs and other foreign matter which is detrimental to the health of the user.

10. The present invention comprehends an individual toothbrush case which includes means constituting a part of the case for containing and disposing an antiseptic sterilizing medium or germicide alongside of the 15 bristles whereby to shield and maintain the brush in a highly sanitary condition at all times.

More specifically, the invention comprehends an individual toothbrush case including 20 a longitudinally split hollow body defining a pair of sections which are relatively movable to an open position for the purpose of inserting or removing a toothbrush, and in which sections pockets are formed in the 25 walls adjacent one end thereof for receiving a pad adapted to contain a germicide or antiseptic sterilizing solution.

Other objects of the invention reside in the 30 simplicity of construction of the case, the economy with which it may be produced and the general efficiency derived therefrom.

With the above recited and other objects in view, reference is had to the following description and accompanying drawings, in 35 which there is exhibited one example or embodiment of the invention, while the claims define the actual scope of the same.

In the drawings—

40. Figure 1 is a perspective view of a toothbrush case constructed in accordance with the invention, illustrating the same suspended from a supporting rack.

Figure 2 is a longitudinal sectional view 45 therethrough taken approximately on the line indicated at 2—2 in Figure 3.

Figure 3 is a similar sectional view taken approximately on the line indicated at 3—3 in Figure 2.

50. Figure 4 is a transverse sectional view

taken approximately on the line indicated at 4—4 in Figure 2.

Referring to the drawings by characters of reference, the case is constructed of a longitudinally split hollow body defining a pair of 55 sections 10 and 11 which are preferably hinged together at 12 at one side whereby the sections may be relatively moved to an open position to insert or remove the toothbrush therefrom. The sections are also provided with suitable means, such as clips 13, 60 for locking the sections in closed mating relation. Adjacent one end 14, each section is of a relatively greater width so that the said end accommodates the bristle end of the 65 toothbrush. At this end, the side walls are suitably formed with pockets 15 which open to the interior of the case and which are designed to accommodate pads 16 saturated with a germicide or antiseptic sterilizing solution. The pockets are preferably formed by applying to the exterior of the side walls the jackets 17 which coincide with openings 18 in the side walls, which openings 18 are of slightly lesser area than the jackets so as 70 to define the flanges 19 which retain the pads 16 in place. At one end, the openings 18 are of increased width as at 20, which width coincides approximately with the transverse dimension of the jacket 17. At the said end, 75 the jacket is formed with an inclined wall 21 so that an entrance mouth is defined, by virtue of which insertion and removal of the pad 16 is facilitated. In order to afford means for suspending the case either from 80 a rack R having the usual notches N or from a nail or hook, one of the sections is formed with a suspension lug 22 having an aperture 85 23.

In practice, the sections 10 and 11 will preferably be constructed of a transparent or semi-transparent material, such as celluloid, by virtue of which the tooth-brush may be identified by the owner without the necessity of opening the case. In this connection, it 90 may be stated that due to the fact that celluloid gives off an odor which is usually offensive and which odor might be absorbed by the toothbrush, the pad 16 saturated with a 95 germicide or antiseptic sterilizing solution 100

will tend to counteract this odor, in addition to performing its usual function. It may also be observed that the case, in addition to its ordinary use in the home, constitutes an ideal container for a toothbrush when traveling which permits of the carrying of the brush either in the pocket or in the baggage of the user.

What is claimed is:

- 10 1. An individual toothbrush case including a pair of hingedly connected casing sections each having a corresponding relatively wider end for the accommodation of the bristle end of the toothbrush and a pocket formed in one of said wider ends opening through and disposed alongside of the point at which the bristles of the brush are positioned, for receiving and holding an absorbent pad for an antiseptic sterilizing medium.
- 15 2. An individual toothbrush case including a longitudinally split hollow body defining a pair of sections relatively movable to an open position for inserting and removing the toothbrush and a pocket formed in the wall of one of said sections adjacent one end thereof, for receiving a pad adapted to contain an antiseptic sterilizing medium.
- 20 3. An individual toothbrush case including a pair of mating hollow sections defining a closed hollow body having an end of restricted cross sectional area to accommodate the handle of a toothbrush and an end of larger cross sectional area to accommodate the bristle end of a toothbrush, said body at its larger end having a pocket in the wall thereof disposed alongside of the point where the bristle end of the brush is positioned and communicating with the interior of the case, said pocket adapted to receive a pad containing an antiseptic sterilizing medium.
- 25 4. An individual toothbrush case including a pair of mating hollow sections defining a closed hollow body having an end of restricted cross sectional area to accommodate the handle of a toothbrush and an end of larger cross sectional area to accommodate the bristle end of a toothbrush, said body at its larger end having a pocket in the wall thereof disposed alongside of the point where the bristle end of the brush is positioned and communicating with the interior of the case, said pocket adapted to receive a pad containing an antiseptic sterilizing medium, said pocket being formed at one end with relatively wider entrance mouth opening into the case for facilitating the insertion and removal of the pad.
